Patented Oct. 26, 1915.

Fig. 3.

Fig. 3. A perspective view of a chain mechanism. It shows a vertical support (10) with a curved arm (11) and a horizontal arm (14). A chain (26) is attached to a sprocket (25) and passes over a pulley (21, 22). The chain then descends and passes through a series of sprockets (28, 25, 20, 16, 17, 19, 12, 28, 25, 15, 24) attached to a curved frame (28). A handwritten note 'Fig. 3.' is written to the right of the drawing.

UNITED STATES PATENT OFFICE.

LOUIS H. LANDRY, OF UXBURG, MASSACHUSETTS.

PATTERN-CHAIN RACK.

1,158,344.

Specification of Letters Patent.

Patented Oct. 26, 1915.

Application filed August 24, 1912. Serial No. 716,836.

To all whom it may concern:

Be it known that I, Louis H. Landry, a citizen of the United States, and resident of Uxbridge, in the county of Worcester and 5 State of Massachusetts, have invented certain new and useful Improvements in Pattern-Chain Racks, of which the following is a specification.

This invention relates to means for supporting the pattern chains of looms for weaving fancy worsted or fancy cassimere goods, and refers especially to the means for supporting the pattern used for the cam box motion. As my present invention is 10 applicable to looms of various kinds, I do not attempt to illustrate or describe herein any details of the loom proper.

The object of the invention is to provide a 15 rack which will enable a chain of great length to be employed within a compact space, the rack providing for the automatic assembling of the portions of the chain which are not operating with the vibrating mechanism, in the form of a series of loops or festoons.

To these ends the invention consists in the chain-supporting rack substantially as hereinafter described and claimed.

Of the accompanying drawings: Figure 1 20 is a plan view of my improved chain rack; Fig. 2 is a side elevation of the same, said figure also illustrating one of the vibrator levers of a loom; Fig. 3 represents a section on line 3—3 of Fig. 2.

Similar reference characters indicate the 25 same or similar parts in all of the views.

To an upright 10, which may be a portion of the frame of a loom, is secured the rack, comprising two brackets 11 having track 30 portions 12. Two guide arms 13, which may be connected together in the form of a yoke, are connected to the brackets 11 by a bolt 14 so that the arms 13 can be adjusted as to their angle relatively to the tracks 12. Rising from the outer ends of the brackets 11 are uprights 15 having their upper ends slotted to permit of the adjustable connection therewith of the guides 16, which, for the purposes of distinguishing them from the lower guide tracks, are hereinafter referred to as the upper guides. Said upper guides have their higher ends supported by a strut 17 having a slotted lower end 18 connected by a bolt 19 to one of the brackets 11, 45 so that said strut 17 may be vertically adjusted. A pin 20 carried by the strut 17

passes through holes in the two upper guides 16. The strut also carries an upper pin 21 adjustably secured in a slot in said strut, the pin having two plates or holders 22, the purpose of which will be presently described. 60

The pattern chain 23 has the usual transverse bars 24 and rolls 25 to act upon the vibrator levers 26 of the loom, said chain being guided over the usual cylinder 29. At 65 certain intervals, some of the bars 24 are longer than the others, the longer bars having mounted upon their outer ends wheels 27 provided with bevel flanges 28. In the drawings I do not attempt to illustrate a 70 chain of the greatest length that may be employed, but I will explain that if the chain contains five hundred bars, preferably every sixty-fifth bar will be longer than the others. As shown in Fig. 1, the two tracks 75 12 are so spaced that only the long bars having wheels 27 can reach from one track to the other, the upper tracks or guides 16 being closer together so that all of the bars will ride thereupon.

In operation the cylinder 29 advances the chain step by step in the direction of the arrow, Fig. 2, all of the bars riding up the upper guides 16 and over the cylinder 29, the cam rolls 25 thereof, acting upon the vibrator 80 levers 26, selecting which levers 26 shall be actuated by the relative spacing of the cam 85 rolls 25 upon the rods, in the usual manner. The holders 22 serve to retain the chain properly upon the upper guides 16 regardless of 80 the amount of jarring to which the rack is subjected by the action of the loom when the rack is supported by the frame of the loom. As the bars of the chain leave the cylinder 29 they pass down upon the guide arms 13, 90 which serve to insure the chain passing down between the brackets 11 without catching upon the latter, and without failing to have the wheels 27 properly reach the tracks 12. As the width of the chain is such that it can 95 pass down between the track brackets 11 said chain will automatically assume the form of loops or festoons, the upper ends of which are defined by the bars that carry the wheels 27. The flanges 28 of the wheels 100 27 are so beveled, as best shown in Fig. 3, as to render it certain that said wheels will be properly guided onto the tracks 12. If the flanges 28 were not beveled, but were simply cylindrical and of greater diameter 105 than the main portions of the wheels, one wheel or the other might ride along on top

of a track 12 and perhaps drop down between the two tracks. As each longer bar carrying the wheels 27 reaches the inner ends of the tracks 12 it will ride along, as will be understood from Fig. 2 of the drawings, but will be finally drawn up between the uprights 15 as the entire chain is pulled onto the upper guides 16. Said upper guides 16 render it certain that the chain 10 will pass over the cylinder 29 with the cam rolls of the rods in proper positions to select the vibrator levers that are to be actuated, the holders 22 preventing the chain from being jarred away from proper position. The 15 upper guides 16 have their upper ends of course extending into close proximity to the flanges of the cylinder 29 so that the chain will pass readily and accurately onto the latter. By the adjustments of the guide 20 arms 13 and the supports for the upper guides 16 at both ends of the latter, I am able to fix the relative positions of the parts to adapt the rack to varying structures of pattern chains.

Having described my invention, I claim:

1. A loom having a pattern chain, a pattern chain cylinder, means located above said

cylinder and operable by said pattern chain, and a supporting rack for said chain comprising upper and lower tracks, the lower tracks being separated by a space greater than the space between the upper tracks, the upper tracks extending into close proximity to said cylinder in position to deliver the chain onto the cylinder.

35

2. A loom having a pattern chain, a pattern chain cylinder, means located above said cylinder and operable by said pattern chain, and a supporting rack for said chain comprising upper and lower tracks, the lower tracks being rigidly connected with the frame of the loom and being separated by a space greater than the space between the upper tracks, the upper tracks being adjustable relatively to the lower tracks and extending into close proximity to the cylinder in position to deliver the chain onto the cylinder.

40

In testimony whereof I have affixed my signature, in presence of two witnesses.

LOUIS H. LANDRY.
